(57) **CLAIM**

The ornamental design for a vehicle fender, as shown and described.

DESCRIPTION

FIG. 1 is a top, and front side perspective view of the first embodiment of a vehicle fender, showing our new design; FIG. 2 is a top, and rear side perspective view thereof; FIG. 3 is a top, and rear inside perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

The second embodiment of the vehicle fender is mirror image of the embodiment disclosed in FIGS. 1 through 9, and is not shown.

1 Claim, 9 Drawing Sheets
